United States Patent Office.

OLIVER VANORMAN, OF RIPON, WISCONSIN.

Letters Patent No. 81,846, dated September 1, 1868.

SPRING-SEAT FOR VEHICLES.

The Schedule referred to in these Letters Patent and making part of the same.

TO ALL WHOM IT MAY CONCERN:

Be it known that I, OLIVER VANORMAN, of Ripon, in the county of Fond du Lac, in the State of Wisconsin, have invented a new and improved Spring-Seat for Vehicles; and I do hereby declare that the following is a full and exact description thereof, reference being had to the accompanying drawings, and to the letters of reference marked thereon.

The nature of my invention consists in providing a seat, mounted upon two elevated wooden bars, one at or near each end of the seat, and fastened upon its under side, these bars having their extreme lower ends resting upon corresponding bars or levers, placed just inside of the wagon-box, parallel with its sides, and the bars upon which the seat rests being secured and held in place, at their connections with the parallel bars, with a hook and eye, or other suitable hinge or joint, making them removable whenever desired. Upon the under edges, and near the lower ends of each of these seat-bars, are placed rubber springs, which rest upon the parallel bars secured to the inner side and near the upper edge of the sides of the wagon-box, these springs receiving the whole weight of the seat, and serving to relieve it from any sudden jar or concussion.

To enable others skilled in the art to make and use my invention, I will proceed to describe its construction and operation.

I make the seat A in any of the commonly-known forms, fastening it rigidly, with screws or bolts, to the upper bevelled ends of the wooden bars or levers, marked B B, these bars extending downward to just inside of the wagon-box, and are secured by hooks and eyes C C, or other suitable attachments, to the upper sides of the parallel bars or levers, represented at D D.

The rubber springs E E are secured into and near the lower ends of the seat-bars B B, either by being made wedge-shaped, and let in grooves or recesses cut in these bars, or by being fastened in any other substantial manner.

The rubber springs E E, being acted upon by compression, are much more durable and efficient than others that yield only by stretching or extension, and in being placed under the elevated bars B B, they are almost wholly protected from the well-known damaging effects of the weather upon rubber when exposed.

The operation of this seat is readily understood, and the proper spring or elasticity is obtained, not altogether from the rubber alone, but in part from the mode of adjustment with the hooks and eyes, and in the use of suitable wooden bars or levers upon which the seat is placed.

The seat and its accessory levers or bars are all easily detached and removed from the wagon-box, when not required for use.

What I claim, is—

The arrangement of the detachable seat, consisting of the elevated levers or bars B B, with hooks and eyes C C, or equivalent devices, to the parallel bars D D, substantially as described.

Also, the arrangement of rubber springs E E, fastened near the lower ends and on the under sides of the elevated seat-bars B B, which rest upon the parallel bars or levers D D.

The above specification of my invention signed by me, this 10th day of July, 1868.

O. VANORMAN.
